UNITED STATES PATENT OFFICE

ARTHUR WM. NELSON, OF PARK RIDGE, ILLINOIS, ASSIGNOR TO LOCOMOTIVE FIRE-
BOX COMPANY, OF CHICAGO, ILLINOIS, A CORPORATION OF DELAWARE

LOCOMOTIVE BOILER

Application filed June 18, 1928. Serial No. 286,444.

This invention relates to improvements in locomotive boilers and especially to those having that type of firebox wherein fuel such as oil is burned and it consists of the 5 matters hereinafter described and more particularly pointed out in the appended claims.

One of the objects of the present invention is to provide in a boiler of this kind, a pair of flat tubular water walls in the firebox 10 thereof, which are connected at their inner rear corners with the boiler barrel and at their outer front corners with the crown sheet of the firebox, whereby a larger superficial heating area is provided and the water steaming and circulating efficiencies of the boiler 15 are materially increased.

The above mentioned objects as well as others, together with the many advantages thereof will more fully appear as I proceed 20 with my specification.

In the drawings:—

Fig. 1 is a longitudinal vertical sectional view through the firebox end of a locomotive boiler embodying my invention.

Fig. 2 is a horizontal sectional view through the same as taken on the line 2—2 of Fig. 1 with the firebrick, burner and associated parts omitted to better disclose the construction and arrangement of the water heating 25 and circulating elements.

Fig. 3 is a transverse vertical sectional view through the firebox end of the locomotive boiler as taken on the line 3—3 of Fig. 1.

Figs. 4 and 5 are transverse vertical detail sectional views through parts of the boiler and firebox on an enlarged scale as 35 taken on the lines 4—4 and 5—5 respectively of Fig. 1.

Referring now in detail to that embodiment of the invention, illustrated in the accompanying drawings, 1 indicates as a whole the barrel of the boiler in which are arranged the usual flues 2. The firebox of the boiler 40 is formed by the flue sheet 3, rear sheet 4, side sheets 5—5 and crown sheet 6, all connected together in the manner well known. In this instance the bottom portion 3a of the flue sheet forms the throat sheet of the firebox.

The firebox wrapper comprises the top plate 7, the side plates 8—8, the outside throat plate 9 and outside back plate 10. The wrapper just described, together with the firebox sheets before mentioned, define the several water legs of the boiler, i. e., the side legs 11—11, the front leg or throat 12, and back leg 13 all closed at the bottom by the usual mud ring 14. The firebox sheets are joined to the wrapper plates by means of stay bolts 15 in the manner well known. 55 16 indicates a door opening which is normally closed by a door (not shown), and this opening provides the fuel door opening in case the firebox is converted into a coal burner as 60 is sometimes necessary and which conversion may be readily made with but comparatively small expense.

In the middle bottom portion of the firebox is provided a novel arrangement of parts 70 forming the water steaming and circulating elements or means, indicated as a whole by the numeral 17 in Fig. 2. Said means comprises a pair of laterally spaced flat hollow elements or walls 18—18 which are disposed, 75 one along the bottom portion of each side water leg and said walls extend downwardly and inwardly therefrom so as to be spaced apart equally on each side of the median line of the firebox.

Each element is in the form of a flat tube or body of a length greater than its width and of a suitable depth, open along its bottom marginal side and closed along its top marginal side by a bulged tubular portion 19. 85 This portion is closed at its rear end but extends forwardly beyond the body to form a flanged discharge neck 20 at said end. The open bottom marginal side of the body is defined by an outwardly flaring flange 21 as 90 best shown in Figs. 4 and 5 and so that said elements may amply resist the internal pressures to which they are subjected in use, they are stay-bolted as indicated at 22.

Associated with the bottom open side of 95 each element body is a tube 23 which is also closed at its rear end but extends forwardly beyond the body to form a flanged intake neck 24. The flange 21 of the associated body seats snugly along one side of said tube and 100

is welded thereto and in the rear end of the tube, in line with the open bottom of the body is an opening 25 as best shown in Figs. 1 and 4. To support said elements in proper 5 position in the firebox, I affix to the firebox side sheets 5—5 shortly above the mud ring, angle bars 26—26 upon which the top bulged portions 19 of each element engages so as to be spaced from the associated side sheet; the 10 space between said side sheets and bulged portions being filled with a suitable refractory material 27. The tubes 23—23 associated with the bodies of said elements rest upon longitudinally spaced straps 28—28 15 which are fixed at their ends to the side parts of the mud ring and the space between said tubes are bridged by a brick arch 29, in which is an opening 30 to provide that amount of air necessary for the burning of fuel in suspension within the firebox.

The inlet tube for each element is connected with the bottom of the boiler barrel by a conduit 31 and to facilitate assembly and to reduce cost of manufacture I preferably 25 make said conduit in more than one section. As best shown in Fig. 1, said conduit comprises a substantially straight tubular section 32 which is fixed at one end to an associated neck 24 and passes beneath the front 30 portion of the mud ring, and an elbow section 33 which is fixed at one end to said section 32 and curves upwardly to be connected to the barrel of the boiler at a point well in advance of the front water leg 12.

35 Preferably said tubular and elbow sections are flanged as shown for attachment, the one to the other.

The front end extension 20 of each top bulged portion is connected to one of the firebox sheets and preferably with the crown sheet by an upright riser or stand-pipe 34. The bottom end of each riser is made with 40 an integral flanged elbow 35 which is fixed to the associated flanged neck 20 while the top end of each riser is fixed in a flexible diaphragm portion 36 formed in the crown sheet as best shown in Figs. 1 and 2.

The elements are disposed midway between the ends of the firebox but spaced therefrom and the space between the front ends of said elements and front portion of the firebox is closed off by a front or burner wall 37 and the space between the rear ends of said elements and the rear portion of the firebox 50 is closed off by a flash wall 38, both walls being made of firebrick. In the front or burner wall is located a fuel nozzle 39 of the oil burner type which projects through an opening 40 in said wall.

60 In operation, the intense heat from the fuel burning in suspension in the firebox over the elements, causes a rapid absorption of heat by the upper surfaces thereof, which heat in turn is taken up by the water in said elements, thus converting part into steam. By

reason thereof, a rapid flow of water from the forward portion of the boiler barrel into the conduits 31 takes place and from there into the tubes 23. This water passes through the opening 25 in the rear end of each tube 70 into the body 18 of each element where it is widely distributed to receive the heat from the products of combustion to be discharged from the diagonally opposite corner thereof, up through the associated riser 34 and then 75 into the boiler water space above the firebox. As the risers or stand-pipes in themselves present a large superficial area to the products of combustion in the firebox, a further heating and steaming action is imparted to the water which augments that action produced in the element bodies. Thus the 80 risers act as siphon-like pumps which assist in the "lift" of the water so that circulation is increased and as these stand-pipes discharge through the crown sheet near its forward end, it is assured that said end of the crown sheet is always flooded with water, even though the boiler water level falls below the normal level. Such water discharged 85 from the stand-pipes being extremely hot will flow forwardly due to the intake from the barrel into the conduits 31 so that the circulation is accelerated and quiet areas within the boiler which makes possible the collection 90 of sediment are eliminated.

The parts are all confined to such dimensions as to make their installation in a locomotive firebox practical and economical and they do not interfere with the numerous other parts of the locomotive. Furthermore, the parts are so disposed in the firebox that they are not subjected to such wide differences in 95 temperatures as will cause them to be seriously affected by resulting strains and stresses.

100 As is apparent the construction described readily lends itself for complete removal from the firebox when it is desired to convert the same into a coal burner.

105 In describing the invention, I have referred in detail to the form, arrangement and construction of the various parts thereof, the same is intended merely by way of illustration so that I do not wish to be limited thereto except as may be specifically set forth in the 110 appended claims.

I claim as my invention:

115 1. A locomotive boiler construction embodying therein a barrel and a firebox having sheets forming parts of the front, rear and side water legs of the boiler, a pair of relatively flat hollow water heating and circulating elements disposed in the firebox and each extending downwardly and inwardly 120 from an associated side sheet, means providing an intake for boiler water from the barrel of the boiler connected to the inner rear end portion of each element and other means providing an outlet for the outer front end portion of each element and opening through one 125

of the sheets of the firebox and discharging into adjacent boiler water space.

2. A locomotive boiler construction embodying therein, a barrel and a firebox having sheets forming parts of the front, rear and side water legs of the boiler, a pair of relatively flat hollow water heating and circulating elements disposed in the firebox and each extending downwardly and inwardly from an associated side sheet, means providing an intake for boiler water from the barrel of the boiler connected to the inner rear end portion of each element and other means providing an outlet for the outer front end portion of each element and rising therefrom and opening through the crown sheet of the firebox into the water space above the same.

3. A locomotive boiler construction embodying therein a barrel and a firebox having a crown sheet, a pair of relatively flat hollow water heating and circulating elements disposed in the firebox and each extending downwardly and inwardly therefrom, conduit means connecting the inner rear end of each element with the barrel of the boiler at a point forwardly of the front water leg thereof and conduit means connected to the outer front end of each element and opening through said crown sheet.

30 4. A locomotive boiler construction embodying therein a barrel and a firebox having a crown sheet, a pair of relatively flat hollow water heating and circulating elements disposed in the firebox and each extending downwardly and inwardly therefrom and each including a flat hollow body open along its bottom rear end and a tubular portion along its outer top end, a tube secured to the open end of each body and having an opening near its rear end in communication with said body, means connecting the forward end of said tubes with said boiler barrel and risers each connected at one end to the top front end of each element and to the crown sheet of the firebox respectively.

45 In testimony whereof, I have hereunto set my hand, this 31st day of May, 1928.

ARTHUR WM. NELSON.
